(57) **CLAIM**

The ornamental design for an outdoor wireless product enclosure for elevated mounting, as shown and described.

DESCRIPTION

FIG. 1 is a perspective view of a first embodiment of an outdoor wireless product enclosure for elevated mounting, in an upright position;

FIG. 2 is a left side view of the outdoor wireless product enclosure for elevated mounting of FIG. 1;

FIG. 3 is a right side view of the outdoor wireless product enclosure for elevated mounting of FIG. 1;

FIG. 4 is a front view of the outdoor wireless product enclosure for elevated mounting of FIG. 1;

FIG. 5 is a back view of the outdoor wireless product enclosure for elevated mounting of FIG. 1;

FIG. 6 is a bottom view of the outdoor wireless product enclosure for elevated mounting of FIG. 1;

FIG. 7 is a top view of the outdoor wireless product enclosure for elevated mounting of FIG. 1;

FIG. 8 is a perspective view of a second embodiment of an outdoor wireless product enclosure for elevated mounting, in a hanging position;

FIG. 9 is a left side view of the outdoor wireless product enclosure for elevated mounting of FIG. 8;

FIG. 10 is a right side view of the outdoor wireless product enclosure for elevated mounting of FIG. 8;

FIG. 11 is a front view of the outdoor wireless product enclosure for elevated mounting of FIG. 8;

FIG. 12 is a back view of the outdoor wireless product enclosure for elevated mounting of FIG. 8;

FIG. 13 is a top view of the outdoor wireless product enclosure for elevated mounting of FIG. 8; and,

FIG. 14 is a bottom view of the outdoor wireless product enclosure for elevated mounting of FIG. 8.

The broken lines are for environment purposes only and form no part of the claimed design.
